UNITED STATES PATENT OFFICE.

JAMES WILLIAM TERRY, OF SAN ANTONIO, TEXAS.

STAMPING-MACHINE.

1,068,947.

Specification of Letters Patent. Patented July 29, 1913.

Application filed February 7, 1912. Serial No. 675,929.

To all whom it may concern:

Be it known that I, JAMES W. TERRY, a citizen of the United States, and a resident of San Antonio, in the county of Bexar and 5 State of Texas, have invented a new and Improved Stamping-Machine, of which the following is a full, clear, and exact description.

The object of the invention is to provide a new and improved stamping machine, more 10 especially designed for use in railroad ticket offices for quickly and accurately stamping railroad tickets on their faces with the date of issue, the destination and the time limit or number of the train on which the ticket 15 is to be used.

For the purpose mentioned use is made of a ticket holder for holding a pile of printed railroad tickets having blank spaces for the date, destination and train number or time 20 limit, a movable ticket support or guide for supporting a ticket at a time, a transferring or feeding device for transferring the ticket singly from the said ticket holder to the said ticket support, revolute printing wheels 25 provided at their peripheral faces with printing characters for printing the destination and train number or time limit onto the face of the ticket held on the said support at a time, an adjustable date stamp adjacent 30 the said printing wheels, means for setting the said printing wheels, and a movable platen adapted to engage the said ticket support and the ticket held thereon to force the latter into printing contact with the 35 printing wheels and the said date stamp to print the destination, the train number or time limit and the date of issue onto the face of the said ticket. Use is also made of an inking roller controlled by the said platen 40 and adapted to pass over an inking pad and the printing characters of the said printing wheels and date stamp.

A practical embodiment of the invention is represented in the accompanying drawings forming a part of this specification, in which similar characters of reference indicate corresponding parts in all the views.

Figure 1 is a plan view of the stamping machine with parts broken out; Fig. 2 is a 50 cross section of the same on the line 2-2 of Fig. 1; Fig. 3 is a longitudinal central section of the same on the line 3-3 of Fig. 1; Fig. 4 is a cross section of the same on the line 4-4 of Fig. 1 and showing the parts in 55 printing position; Fig. 5 is a cross section

of the ticket holder, the section being on the line 5-5 of Fig. 3; Fig. 6 is an enlarged plan view of the holder for the printing characters of the date stamp; Fig. 7 is an enlarged side elevation of the pusher for pushing a ticket from the ticket holder into the ticket support or guide; and Fig. 8 is a face view of one of the tickets after being printed on, to supply the date of issue, the destination and the train number or time 65 limit.

On a suitably constructed casing A is mounted to swing up and down a platen B adapted to engage a slotted ticket support or guide C adapted to support a printed railroad ticket D with the printed face downward. The platen B on being moved downward causes a downward sliding of the support C and with it moves the ticket D to press the printed face of the ticket into 70 printing contact with a fixed date stamp E, the peripheral faces of a set of spaced revolute printing wheels F, F', and with a second set of spaced revolute printing wheels G, G' located intermediate the printing 75 wheels F and F', as plainly indicated in Figs. 1 and 3.

The ticket D as supplied to a station agent is printed with the usual legend and provided with blank spaces on which are printed 80 the date of issue D' once, the destination D², D³ twice and the train number or time limit D⁴, D⁵ twice, as plainly indicated in Fig. 3. The date stamp E is provided with removable printing characters or type E' 85 for printing the date of the issue D' on the ticket D, the revolute printing wheels F and F' are provided on their peripheral faces with printing characters F², F³ for printing the destinations D², D³ onto the ticket D, 90 and the printing wheels G and G' are provided on their peripheral faces with printing characters G², G³ for printing the train number or time limit D⁴, D⁵ onto the ticket D. The printing characters F², F³ of the 95 printing wheels F and F' represent the different stations along the railroad on which the issuing station is located, and the said printing wheels F and F' are manually controlled so as to bring the printing characters F² and F³ of any desired station into uppermost or printing position, it being understood that the printing characters F², F³ in printing position at the time are alike, that is, represent like names of the same station. 100 105 110

In order to turn the printing wheels F and F' in unison with a view to bring the printing characters of the desired station into top or printing position, the following arrangement is made: The printing wheels F and F' are secured on a longitudinally-extending shaft F⁴ journaled in suitable bearings on the casing A, and on the ends of the shaft F⁴ are secured pinions H in mesh with 10 segmental gear wheels H' secured on short shafts H² journaled in suitable bearings on the casing A. The segmental gear wheels H' are provided with arms H³ connected with each other by a bar H⁴ supporting an upwardly-extending arm H⁵ carrying a stud H⁶ provided with a pointer H⁷ indicating on the names of the stations F⁵ arranged on a cover A' hinged at its lower end at A² to the front end of the base A³ of the casing A. 15 The cover A' is provided with a slot A⁴ through which extends a shank H⁶ of the pointer H⁷ so that the latter is on the outside of the cover A' and readily points on the names of the stations F⁵, which latter are arranged in such a manner relative to the printing characters F and F' that when the pointer H⁷ points at any one name of the stations F⁵, the same name of the station is 20 represented by the printing characters F² and F³ in top or printing position. A handle H⁸ extends from the arm H⁵ through the slot A⁴ to the outside of the cover A', so that the operator on taking hold of the handle H⁸ can swing the arms H² up or down, 25 whereby the segmental gear wheels H' are rotated and consequently the pinions H turn the shaft F⁴ and with it the printing wheels F and F' with a view to bring the printing characters F², F³ into top or printing position. 30 A spring brake arm H⁹ is held on the arm H⁵ and bears against the inner face of the cover A' to hold the printing wheels F and F' in the adjusted position.

The printing wheels G and G' are secured on a shaft G⁴ journaled in suitable bearings arranged on the casing A, and on the said 35 shaft intermediate the printing wheels G and G' is secured a gear wheel I (see Figs. 1, 3 and 4) in mesh with a gear wheel I' having its shaft I² journaled in suitable bearings on the casing A, and the said gear wheel I' is 40 in mesh with a pinion I³ secured on a shaft I⁴ journaled in suitable bearings arranged on the casing A. The left-hand end of the shaft I⁴ extends through the corresponding side of the casing A, and on the outer end 45 of the said shaft is secured a knob I⁵ under the control of the operator for turning the shaft I⁴ with a view to rotate the printing wheels G and G' by the gearing above described. On the shaft I⁴ adjacent the left-hand side of the casing A is arranged an in-

dicating wheel I⁶ provided on its peripheral face with numerals I⁷ adapted to successively appear through an opening A⁵ formed in the cover A'. The numerals I⁷ correspond to the numerals of the printing characters G², G³ on the peripheral faces of the printing wheels G and G', and the arrangement is such that when a numeral I⁷ (say 1) appears in the opening A⁵ then the corresponding numeral "1" on the printing characters G², G³ appears on top or printing position in longitudinal alinement with the characters F and F' and the type E' of the date stamp E.

The ticket support C is in the form of a plate provided on top with a slot C' through which appear the printing characters F², F³, G², G³ in uppermost or printing position, at the time, and the sides of the said plate are provided with raised guideways C² to 80 guide the ticket into proper position when moved from the right to the left as herein-after more fully explained. The ends of the ticket support C are provided with downwardly-extending members C³ slidably engaging guideways A⁶ arranged on the frame (see Fig. 2), and the members C³ are provided with downwardly-extending rods C⁴ slidably engaging guideways C⁵ attached to the casing A. Springs C⁶ are coiled on the rods C⁴ and rest on the bearings C⁵ so as to normally hold the ticket support C in an uppermost position, that is, a distance above the printing wheels F, F', G, G'. When the platen B is swung downward it engages the ticket support C and moves the same downward against the tension of the springs C⁶, and when the platen B is swung upward the ticket support C is returned to its uppermost position by the action of the springs C⁶. 100

Tickets D, with blank spaces thereon for the date, the destination and the train number or time limit, are arranged in a pile, with the faces downward, in a ticket holder J removably attached to the right-hand side 110 of the casing A in longitudinal alinement with the ticket support C and the axes of the printing wheels F, F', G, G'. The ticket holder J is in the form of an oblong box and contains a vertical movable bottom J' supported on ropes J² extending upward and passing over guide pulleys J³ arranged in the upper portion of the holder J. The ropes J² are provided with overbalancing weights J⁵ so as to cause the upward movement of the bottom J' with a view to raise the pile of tickets D and cause the uppermost tickets to abut against rollers J⁶ (see Fig. 5) held on guideways J⁷ attached to the ticket holder J. A pusher K is mounted to slide in the guideways J⁷ and is adapted to engage the uppermost ticket D and push the same off the pile of tickets and onto the ticket support C, and for this purpose the guideway J⁷ extends beyond the 115 120 125

ends of the ticket holder J to permit the pusher K to pass into a right-hand end position with its bottom flush with the under side of the uppermost ticket D, as will be 5 readily understood by reference to Fig. 3, so that the right-hand edge of the uppermost ticket abuts against the left-hand end of the pusher K, and this left-hand end of the pusher K is provided above its bottom with a forwardly-projecting tongue K' adapted to rest on the upper surface of the uppermost ticket D. Now when the pusher K is moved from its right-hand end position to the left then the uppermost ticket 15 K is pushed off the pile of tickets in the holder J and onto the support C to be printed on, on swinging the platen B downward, as previously explained.

The pusher K is actuated from the platen B, and for this purpose the following arrangement is made: On the top of the pusher K is arranged a pin K² engaging the slotted end K³ of a lever K⁴ fulcrumed at K⁵ on the casing A, and the lever K⁴ is pivotally connected by a link L with a lever L' fulcrumed at L' on top of the casing A. The lever L' is pivotally connected by a short link L³ with a cam lever L⁴ fulcrumed at L⁵ on the top of the casing A, and the 30 said cam lever L⁴ extends under the arm B' of the platen B so that when the latter is swung downward a swinging motion is given to the cam lever L⁴ which by the link L³ imparts a swinging motion to the lever L' and the latter by the link L imparts a swinging motion to the lever K⁴ to swing the latter from the left to the right, that is, from an innermost position to an outermost position as shown in full lines in Fig. 1. A 35 spring K⁶ is connected with the lever K⁴ to swing the latter from the right to the left on swinging the platen B into an uppermost position so that the uppermost ticket is moved from the holder J onto the ticket 40 support C. The swinging movement of the lever K⁴ from the right to the left by the action of the spring K⁶ is limited by a stop K⁷ on top of the casing A.

The guideway J' is preferably hinged at 45 its right-hand end to the holder J, to permit of swinging the guideway J' into a vertical position whenever it is desired to fill the holder J with tickets. The left-hand end of the guideway J' is fastened in place on the 50 top of the holder by pivoted buttons J⁸, which when swung to one side permit of swinging the guideway J' into an open position for the purpose mentioned.

In order to ink the printing characters E', 55 F², F³, G², G³, use is made of an inking roller N journaled at its ends in arms N' fulcrumed at N² on the casing A, and the said arms N' are engaged by loops N³ (see Figs. 2 and 4) held on a lever N⁴ fulcrumed 60 at N⁵ and pivotally connected with an arm

N⁶ attached to and forming part of the arm B' of the platen B. The inking roller N is adapted to pass over a segmental inking pad O carried on the frame, and when the platen B is in an uppermost position, as 70 shown in Fig. 2, then the inking roller N is in a forward position, and when the platen B is swung downward then the arm N⁶ imparts a swinging motion to the lever N⁴ which by the loops N³ imparts a swinging 75 motion to the arms N' to move the inking roller N rearward and over the printing characters E', F², F³, G² and G³ in uppermost position at the time, the inking roller N finally moving in engagement with the 80 pad O to take up ink therefrom. When the platen B swings back into an uppermost position then the inking roller N is carried forward and again passes over the faces of the printing characters in uppermost position at the time. Thus by the arrangement 85 described, an automatic thorough inking of the printing characters takes place to insure proper impressions on the ticket D. A spring N⁷ is connected with the lower end 90 of the lever N⁴ to insure a return movement of the inking roller N to dormant position as shown in Fig. 2.

The operation is as follows: When the holder J is filled with tickets D as described, 95 and the station agent at San Antonio, for instance, desires to issue a ticket, say to the station Serbin, on January 1, 1912, good for train No. 1, then the operator takes hold of the handle H⁸ and moves the same up or down until the pointer H⁷ indicates on the station Serbin found under the names F⁵, as shown in Fig. 1, the same names now appearing in top position on the printing wheels F and F'. The operator now takes 100 hold of the knob I⁹ and turns the same to revolve the printing wheels G, G' until the numeral "1" appears on top or printing position. The date stamp E was set to January 1, 1912, and the operator now 105 swings the platen B downward so that a ticket D held on the ticket guide C from a previous operation of the feeding mechanism is pressed downward into printing contact with the date stamp E, the printing characters F², F³, G² and G³ to make an impression on the ticket, to provide the same with the name "Serbin" in two places, the train numbers or time limits in two places, and the date of issue, as plainly indicated 110 in Fig. 8. During the downward swinging movement of the platen B, an outward traveling motion is given to the pusher K, and when the platen B is swung upward then the ticket support C with the printed ticket 115 thereon is returned to uppermost position by the action of the springs C⁶ as previously explained, and the pusher K is moved from the right to the left by the action of the spring K⁶ so that the uppermost ticket in 120

130

the ticket holder J is now pushed from the right to the left against the right-hand end of the ticket in the ticket support C, whereby this ticket is pushed from the right to 5 the left a sufficient distance out of the support C to permit the operator to remove the printed ticket from the machine while another ticket is placed in position on the support C. The machine is now ready for 10 repeating the above-described operation.

Having thus described my invention, I claim as new and desire to secure by Letters Patent:—

1. A stamping machine, comprising a 15 ticket holder for holding a pile of printed railroad tickets having blank spaces for the date, destination, and train number or time limit, a movable ticket support adjacent the said ticket holder, revolute printing wheels 20 provided at their peripheral faces with printing characters for printing the destination and the train number or time limit onto the face of a ticket held at the time in the said support, a changeable date stamp 25 adjacent the said printing wheels, a movable platen adapted to engage the said ticket support and the ticket held thereon and move the latter into printing contact with the said printing wheels and date stamp to 30 print the date of issue, the destination and the train number or time limit onto the face of the ticket, and a feeding device controlled by the said platen for feeding a ticket from the said holder into the said 35 ticket support.

2. A stamping machine, comprising a ticket holder for holding a pile of printed railroad tickets having blank spaces for the date, destination and train number or time 40 limit, a movable ticket support adjacent the said ticket holder, revolute printing wheels provided at their peripheral faces with printing characters for printing the destination and the train number or time 45 limit onto the face of a ticket held at the time in the said support, a changeable date stamp adjacent the said printing wheels, a movable platen adapted to engage the said ticket support and the ticket held thereon and move the latter into printing contact with the said 50 printing wheels and date stamp to print the date of issue, the destination and the train number or time limit onto the face of the ticket, and a feeding device 55 controlled by the said platen for feeding a ticket from the said holder into the said ticket support during the return movement of the platen.

3. A stamping machine, comprising a 60 ticket holder for holding a pile of printed railroad tickets having blank spaces for the date, destination and train number or time limit, a movable ticket support adjacent the said ticket holder, revolute printing wheels 65 provided at their peripheral faces with

printing characters for printing the destination and the train number or time limit onto the face of a ticket held at the time in the said support, a changeable date stamp adjacent the said printing wheels, a movable platen adapted to engage the said ticket support and the ticket held thereon and move the latter into printing contact with the said printing wheels and date stamp to print the date of issue, the destination and 70 the train number or time limit onto the face of the ticket, a feeding device controlled by the said platen for feeding a ticket from the said holder into the said ticket support, manually-controlled means for setting the 80 revolute printing wheels for printing the destination, and manually-controlled means for setting the printing wheels for printing the train number or time limit.

4. A stamping machine, comprising a 85 ticket holder for holding a pile of printed railroad tickets having blank spaces for the date, destination and train number or time limit, a movable ticket support adjacent the said ticket holder, revolute printing wheels 90 provided at their peripheral faces with printing characters for printing the destination and the train number or time limit onto the face of a ticket held at the time in the said support, a changeable date stamp adjacent the said printing wheels, a movable platen adapted to engage the said ticket support and the ticket held thereon and move the latter into printing contact with the said 95 printing wheels and date stamp to print the 100 date of issue, the destination and the train number or time limit onto the face of the ticket, a feeding device controlled by the said platen for feeding a ticket from the said holder into the said ticket support, an inking roller for inking the said printing rollers, a fixed inking pad, and means carrying the said inking roller and connected with the said platen for moving the said inking roller over the inking pad, and the 110 printing characters of the printing wheels on imparting movement to the said platen.

5. A stamping machine, comprising a set of spaced printing wheels mounted to turn in unison and provided at their peripheral faces with spaced printing characters representing the names of stations, a second set of spaced printing wheels mounted to turn in unison intermediate of the printing wheels of the first set of printing wheels 115 and independent thereof, the said second set of printing wheels being provided at their peripheral faces with aligned printing characters representing train numbers or time limits, a platen mounted to swing toward and from the peripheral faces of the said printing wheels, a spring-pressed ticket support mounted to slide toward and from the peripheral faces of the said printing wheels and located intermediate the said printing 120 125 130

wheels and the platen to be engaged and moved by the latter.

6. A stamping machine, comprising a set of spaced printing wheels mounted to turn in unison and provided at their peripheral faces with alined printing characters representing the names of stations, a second set of spaced printing wheels mounted to turn in unison intermediate of the printing 10 wheels of the first set of printing wheels and independent thereof, the said second set of printing wheels being provided at their peripheral faces with alined printing characters representing train numbers or time 15 limits, manually-controlled means for setting the said printing wheels, a platen mounted to swing toward and from the peripheral faces of the said printing wheels, a spring-pressed ticket support mounted to 20 slide intermediate the said printing wheels and platen and adapted to be moved by the latter, an inking roller, an inking pad, and means carrying the said inking roller and connected with the said platen to move the 25 inking roller over the said pad and the said printing characters on the printing wheels.

7. A stamping machine, comprising a set of spaced printing wheels mounted to turn in unison and provided at their peripheral 30 faces with alined printing characters representing the names of stations, a second set of spaced printing wheels mounted to turn in unison intermediate of the printing wheels of the first set of printing wheels and independent thereof, the said second set of printing wheels being provided at their peripheral faces with alined printing characters representing train numbers or time 35 limits, a ticket holder adjacent the said printing wheels and adapted to contain a pile of tickets, the said ticket holder having an overbalanced bottom for the tickets to rest on, a ticket support mounted to slide above the said printing wheels, springs supporting the said ticket support and normally holding the said support in horizontal alignment with the upper end of the ticket holder, a platen mounted to swing and adapted to engage the said ticket support 40 to press the latter toward the printing wheels, and a feeding device movable over the said ticket holder and controlled by the 45

said platen for moving a ticket from the holder into the said ticket support.

8. In a stamping machine, a printing 55 mechanism including a swinging platen, a ticket holder, a reciprocating pusher for feeding the tickets from the holder to the printing mechanism, a pivoted and spring pressed lever pivotally connected with the 60 pusher, a second lever connected to the first lever by a link, and a cam lever operated by the platen and connected with the second lever by a link.

9. In a stamping machine, a printing 65 mechanism including a pivoted platen carrying member, pivoted arms carrying an inking roller, a pivoted and spring pressed lever with which said arms are slidably connected, and an arm rigid with the platen 70 carrying member and pivotally connected with said lever.

10. In a stamping machine, a slotted casing, printing wheels mounted in the casing, said casing having names arranged relatively to the printing characters of the wheels on its exterior adjacent to the slot, gearing for operating the wheels, arms carried by two of the wheels of the gearing and connected by a bar, a member extending 75 from the connecting bar of the arms, and a pointer carried by said member and having its shank working in the slot of the casing.

11. In a stamping machine, a slotted casing having names on its exterior adjacent to the slot, printing wheels mounted in the casing, pinions on the shaft of the said wheels, segmental gear wheels meshing with the pinions and having connected arms, an 80 upwardly extending arm on the connecting member of said arms, a pointer carried by said arm and having its shank working in the slot of the casing, a handle secured to the said arm and extending through the 85 slot of the casing, and a spring carried by said arm and bearing against the casing.

In testimony whereof I have signed my name to this specification in the presence of two subscribing witnesses.

JAMES WILLIAM TERRY.
